UNITED STATES PATENT OFFICE.

HENRY A. TOWNSON, OF BINGHAM, NEBRASKA.

SWIVELED TELESCOPING WAGON-REACH.

1,193,946.

Specification of Letters Patent. Patented Aug. 8, 1916.

Application filed February 16, 1915. Serial No. 8,554.

To all whom it may concern:

Be it known that I, HENRY A. TOWNSON, a citizen of the United States, residing at Bingham, in the county of Sheridan and State of Nebraska, have invented certain new and useful Improvements in Swiveled Telescoping Wagon-Reaches; and I do hereby declare the following to be a full, clear, and exact description of the invention, such as will enable others skilled in the art to which it appertains to make and use the same.

The invention relates to a swiveled telescoping wagon reach.

The object of the present invention is to improve the construction of vehicle running gear and to provide a simple, inexpensive and efficient swiveled telescoping wagon reach of practically indestructible construction adapted to be lengthened or shortened approximately eight feet more or less without the addition of an extra piece for the removal of the same from the reach and without interfering with the tracking of the front and rear wheels of a wagon.

A further object of the invention is to provide a telescoping reach of this character which when taken up will not extend from the rear of a vehicle and cause annoyance and inconvenience.

With these and other objects in view the invention consists in the construction and novel combination and arrangement of parts hereinafter fully described, illustrated in the accompanying drawings and pointed out in the claim hereto appended, it being understood that various changes in the form, proportion and minor details of construction may be resorted to without departing from the spirit or sacrificing any of the advantages of the invention.

In the drawing Figure 1 is a plan view of a portion of a running gear provided with a swiveled telescoping reach constructed in accordance with this invention, Fig. 2 is a transverse sectional view on the line 2—2 of Fig. 1, Fig. 3 is a detail perspective view of one of the sections of the swivel bearing, Fig. 4 is a detail perspective view illustrating the construction of the sleeve or coupling which is swiveled in the bearing of the rear.

Like numerals of reference designate corresponding parts in all the figures of the drawing.

In the accompanying drawing in which is

illustrated the preferred embodiment of the invention, the reach comprises in its construction, front and rear tubular sections 1 and 2, the front section 1 telescoping into the rear section 2 and adapted to be moved inwardly and outwardly to vary the length of the reach. The front section 1 is provided at its front end with a head 3 designed to be constructed of malleable metal or other suitable material and having a shank 4 which is secured by rivets or other suitable fastening means in the front end of the front section 1 of the reach. The head 3 is provided with an opening 5 which is adapted to receive the king bolt of the front truck or portion of a vehicle.

The front and rear sections 1 and 2 may be of any relative length and the rear section is provided at its front end with a sleeve or coupling 6 provided with an exteriorly arranged collar, cast or otherwise formed on the sleeve or coupling 6 which is interiorly threaded to screw on the front end of the rear section 2 and also to receive a short end piece 8. The short end piece 8 which is screwed into the front end of the sleeve or coupling 6 is provided with aligned perforations for the reception of a coupling pin 9 which is also adapted to be arranged in any one of a series of perforations 10 of the front reach section. The perforations 10 are arranged at intervals and may be of any desired number to secure the requisite adjustment of the front and rear reach sections.

The sleeve or coupling 6 which is designed to be constructed of malleable metal or other suitable material is swiveled in a bearing composed of upper and lower sections 11 of similar construction provided with longitudinal channel or bearing recesses 12 to receive the sleeve or coupling 6 and having registering transverse grooves 13 which are engaged by the annular flange 7. The sections 11 of the bearing are provided at opposite sides with laterally projecting attaching flanges 14 arranged in substantially flush relation with the upper face of the upper section and the lower face of the lower section and spaced apart to receive the front terminals of the rear hounds 16 to which they are secured by bolts or other suitable fastening devices. The sections of the swivel bearing form hound plates for connecting the rear hounds 13 of the running gear.

The swivel connection between the rear

hounds and the reach will permit a complete rotary movement of the rear truck of the running gear and the longitudinal adjustment of the sections of the reach do not interfere with the tracking of the front and rear wheel of the vehicle and when the reach is shortened it will not extend from the back of the vehicle. Also by means of the telescopic sections a relatively great adjustment 10 of the reach is secured without the necessity of adding an extra piece to the running gear or removing the same therefrom.

What is claimed is:

15 A device of the class described including a rear bearing having means for securing it to the rear hounds of a running gear, said bearing being provided with an interior annular groove, a reach composed of front and rear sections, a sleeve screw-threadedly fitted 20 on the front end of said rear section, a collar screw-threadedly mounted on the oppo-

site end of said sleeve and projecting beyond the same, said collar provided with an opening therein, said front section provided with a plurality of spaced openings slidably 25 mounted through the collar into the rear section, a pin in the opening of the collar adapted to be inserted into the openings of the front section for holding the same in any desired adjusted position, means on said sleeve fitting into the groove of said bearing holding the same against longitudinal movement, a head having a shank secured in the front end of the front reach sections and means for securing the reach sections in 30 their adjustment.

In testimony whereof I affix my signature in presence of two witnesses.

HENRY A. TOWNSON.
